UNITED STATES PATENT OFFICE.

CHARLES BOBER, OF NEW BRITAIN, CONNECTICUT, ASSIGNOR OF ONE-HALF TO
THOMAS KOBYNOS, OF NEW BRITAIN, CONNECTICUT.

AUTO HOOD LOCK.

Application filed January 18, 1923. Serial No. 613,319.

To all whom it may concern:

Be it known that I, CHARLES BOBER, a citizen of Poland, residing at New Britain, in the county of Hartford and State of Connecticut, have invented certain new and useful Improvements in Auto Hood Locks, of which the following is a specification.

My invention relates to improvements in auto-hood locks having reference to the 10 clamp structures that are used on automobiles for clamping the hood in the closed position over the engine structure and adjacent parts and the object of my improvement is to incorporate in the structure of a 15 hood-clamp a key controlled lock so as to prevent unauthorized opening of the hood and tampering with the engine or other parts such as are usually enclosed within the hood, involving the use of one or more 20 clamps in accordance with my improvement on each side of the hood and replacing a corresponding number of the clamps of ordinary form.

In the accompanying drawing:—

Figure 1 is a side elevation of part of the structure of an automobile showing the hood and the adjacent part of the chassis and with a hood clamp made in accordance with my invention, provided with a key-controlled 30 lock, the key also being shown in place.

Figure 2 is a similar view on an enlarged scale of the hood-clamp shown in Fig. 1 and adjacent parts.

Figure 3 is a plan view of the same.

Figure 4 is a similar view with the top cap turned to the closed or covering position.

Figure 5 is a front view of the same.

Figure 6 is a sectional view on the line 40 6—6 of Fig. 3.

Figure 7 is a similar view with the parts in the unlocked position and the hook free to be turned on its axis.

My improved auto-hood lock involves the 45 use of a structure that comprises essentially the combination of an auto-hood clamp structure 10 and a key-controlled lock structure 11 and which structures are intimately associated, as will be described.

The clamp structure or clamp proper 10 is 50 pivotally connected by its lower end 12 with the chassis 13 and has at its upper end a laterally positioned and downwardly directed hook 14 that in the locked position is engaged with an opening 15 in an eye piece

or lug 16 that is supported from the side wall of the hood 17.

Said hook 14 comprises the laterally directed connecting portion 18 that extends outwardly from the adjacent side wall 19 and the free arm 20 that extends downwardly from the outer end of said connecting portion 18, said free arm being the part that is actually engaged with the opening 15. Between the free arm 20 and the adjacent 60 side wall 19 is an open space 21 in which is housed the end wall or enclosing wall 22 of the eye structure or eye lug 16, and which space 21 is substantially filled by said lug 16.

As will be described, the lug 16 serves as 70 the keeper for the lock structure 11 and to this end it is provided in the end face that is opposed to the side wall 19 with an opening 23 that is adapted to cooperate with the engaging free end of the locking bolt 24. 75

Like the hood clamps in common use the hood clamp structure 10 is composed of two main parts that have overlapping and loosely telescoping portions and that are held operatively positioned one relatively to the 80 other by means of a coil spring 25.

Said parts comprise the upper part 26 that carries the hook 14 and the lower part 27 that has the pivotally connected lower end 12. 85

The lower part 27 above the hinge connection or pivotal connection is generally in the form of a rod that terminates at the upper end in the form of a head 28 that cooperates with the opposed upper end of the 90 spring 25.

The upper part 26 comprises a body portion 29 of appreciable length and of generally cylindrical form of larger diameter than the rod structure of the lower part 27, 95 has the hook 14 adjacent the upper end, supported by the connecting portion 18, and has just below said connecting portion 18 a transversely directed chamber 30 for the bolt 24 and for a backing spring 31 for said 100 bolt.

The lower end portion of the body portion 29 overlaps the lower part 27 and has an internal chamber 32 that is closed at the bottom by means of a head 33 and in which 105 chamber 32 is housed the spring 25 and the cooperating portion of the lower part 27.

As described and as is common, the upper part 26 and the lower part 27 are connected by means that permit of lifting the hook 14 110

so as to disengage from the eye structure provided by the lug 16 and then turning the hook to one side, the lifting being in opposition to the spring 25, which tends to draw the parts together.

At the extreme upper end of the body portion 29 is a laterally directed hook-like handle lug 34 that is convenient in manipulating the clamp structure.

10 The body portion 29 may be extended upwardly appreciably to provide material for the lock.

15 A cap 35 is provided that is adapted to swing to one side and that normally serves as a closure or cover for the extreme end face of the body portion 29, being provided with a pivotal connection 36 that is positioned adjacent the handle 34. Said pivotal connection 36 comprises a spring 37 that 20 serves to provide a yielding connection for the parts.

25 The lock structure corresponds generally to the form known as a cylinder or pin lock. As shown, said lock structure has a key 38 of generally flat form with the usual undulating operating edge for operating a set 39 of spring-pin tumblers. The key 38 serves to release the cylinder or barrel 40 so that the same can be rotated. Adjacent the lower 30 end of the barrel 40 is a slot 41 in the periphery that cooperates with a positioning pin 42 that serves to position and also to limit the rotative movement of the barrel 40.

35 The extreme lower end portion 43 of the barrel 40 is operatively connected with the bolt 24 in any proper manner as by means of cooperating cam portions or the equivalent.

The parts are constructed and arranged

so that when the clamp structure is brought 40 to the proper clamping position for holding the hood in place and released the bolt will engage with the keeper provided by the lug 16 and in order to release the clamp it will be necessary to use the key for operating 45 the lock.

I claim as my invention:—

1. In combination in an auto-hood lock structure, a chassis of an automobile and a 50 hood supported thereby, said hood having a laterally directed lug that has an eye opening, a hood-clamp structure of generally vertically elongated form that is pivotally connected by its lower end to said chassis and is provided at its upper end 55 with a hook for being engaged with said eye opening, said hood-clamp structure comprising two main parts that are connected for relative movement, said parts comprising an upper part that supports said hook and a lower part that has the above mentioned pivotally connected lower end, said 60 lug and upper part having in the engaged position opposed and adjacent wall portions, a lock supported by said upper portion, and said lock having a bolt for locking together said opposed and adjacent wall 65 portions.

2. In an auto-hood lock structure as described in claim 1, said upper part having a laterally directed handle lug at the upper end and having a key-hole opening in the upper face, and a key-hole cover pivotally supported by said handle lug and adapted 70 to be swung over and cover said key-hole 75 opening.

CHARLES BOBER.
